PREDIRECTING SYSTEM FOR TORPEDOES.

1,418,851.

Specification of Letters Patent. Patented June 6, 1922.

Application filed June 20, 1917, Serial No. 175,849. Renewed January 14, 1921. Serial No. 437,360.

To all whom it may concern:

Be it known that I, ALBERT D. TRENOR, a citizen of the United States, and a resident of the city, county, and State of New York, have invented certain new and useful Improvements in Predirecting Systems for Torpedoes, of which the following is a specification.

Some of the objects of this invention are to provide in a predirecting system for torpedoes means whereby the torpedo may be predirected while it is being fired or discharged from a relatively stationary torpedo tube or other suitable support; to provide an improved system for predirecting and launching torpedoes, comprising a torpedo tube or other basal support, means for projecting a torpedo from the tube or support, means rendered operative as a result of the outward movement of the torpedo within its tube or support for initiating and accelerating the rotation of the rotor of a gyroscope or other directing means carried by the torpedo, and means for rotatively adjusting an azimuth ring or other element cooperating with the gyroscope to predirect the torpedo while the torpedo is being forced outwardly within the tube and while the rotary movement of the rotor is being accelerated, and up to the point in the movement of the torpedo where the rotor of the gyroscope has reached a certain predetermined speed; and to provide other improvements as will appear hereinafter.

In the accompanying drawings Fig. 1 is a fragmentary side elevation, partly in vertical section, of a system constructed in accordance with this invention for predirecting and discharging a torpedo; and Fig. 2 is a diagrammatic top plan view of a portion of the same.

Referring to the drawings, one embodiment of this invention comprises a torpedo tube 10 which may be stationarily mounted in any suitable manner upon a torpedo boat or upon any other suitable support. This tube is arranged to contain a torpedo 15 of any well known or suitable construction, and is provided at its inner end with an inlet 16 which communicates through a pipe 17 with a tank 18 or other source of compressed air for discharging the torpedo 15 from the tube 10 in a well known manner, the discharge of the torpedo from the tube 10 being con-

trolled by a valve 20 which controls the pipe 55 17 and which is arranged in any convenient position.

The torpedo 15 comprises a hollow shell 25 of any well known or suitable construction, which is provided with one or more 60 propellers 26 arranged to be actuated by a shaft 27 which is driven by any suitable motor carried by the torpedo.

The torpedo 15 is also provided with a pair of normally vertical rudders 35 and 36 65 which are arranged to oscillate about normally vertical axes and to be controlled in a well known manner by two connecting rods 37 and 38 which are arranged to be actuated respectively by two spring pressed pistons 70 39 and 40 which are arranged in stationary cylinders 41 and 42. The outer ends of these two cylinders are connected by a pipe 45 and their inner ends are connected by a pipe 46, and these two pipes are arranged to receive air from two pipes 47 and 48 respectively which communicate through a stationary valve casing 50 and pipe 51 with a tank 55 or other source of compressed air. The inlet of the air into and the exhaust of 80 air from the opposite ends of the two cylinders 41 and 42 are controlled by a valve 60 which is arranged to reciprocate in the casing 50 and which is controlled by two solenoids 61 and 62 which are arranged to be 85 controlled in a well known manner by an azimuth ring 65 which is arranged within a casing 66 to rotate with respect thereto about a normally vertical axis.

The casing 66 contains a gyroscope 70 90 which is arranged to control a conducting arm 71 which is arranged to swing about a normally vertical axis coincident with the vertical axis of the azimuth ring 65 and which has its free end arranged to slide over the azimuth ring 65 which is divided into two approximately semi-circular segments 72 and 73 which are insulated one from the other, and which are connected respectively by conductors 74 and 75 with the outer ends 100 of the two solenoids 61 and 62. The swinging arm 71 is connected by a conductor 76 to one pole of a battery 77, the other pole of which is connected by a conductor 78 and branch conductor 79 with the two inner ends 105 of the solenoids 61 and 62. By this arrangement, when the torpedo 15 swings with respect to the arm 71 which is caused to point

in a fixed direction by the gyroscope, the arm 71 will make contact with one or the other of the segments 72, 73 and will energize the corresponding solenoid 61 or 62 to steer the 5 torpedo accordingly.

The gyroscope 70 includes a rotor 80 which is mounted in a normally horizontal gimbal ring 81 which is mounted to swing about a normally horizontal axis in a normally vertical gimbal ring 82, the two gimbal rings 81 and 82 forming a part of the gyroscope. For rotating the rotor 80, the rotor is provided with a pinion 85 rigid therewith, which is engaged by a pinion 86, 15 which is coaxial with and rigidly secured to an elongated pinion 87, which is arranged in a horizontally reciprocatory sleeve 88. The elongated gear 87 and the pinion 86 rigid therewith are rotated independently of the 20 sleeve 88 by means of a turbine 90 which is actuated by compressed air delivered into the turbine through a pipe 91 which leads from the tank 55, and which is controlled by a valve 92 which is arranged to be controlled 25 by a trigger 93 which is shown in its closed position in Fig. 1, and which is arranged to be moved into engagement with the stationary lug 94 to open the valve 92 as the torpedo is forced out of the torpedo tube 10. 30 For holding the gimbal rings 81 and 82 of the gyroscope 70 fixed with respect to the torpedo 15 while the torpedo is at rest in the tube 10, and until it has been partially discharged from the tube, and until the 35 rotation of the rotor 80 has been initiated and accelerated up to a predetermined speed, and then for automatically releasing the gimbal rings and the rotor 80 carried thereby, a pin 100 is arranged to reciprocate 40 in a fixed path into and out of engagement in an opening provided therefor in the normally horizontal gimbal ring 81. This pin 100 is connected to the upper portion of a lever 105 which is arranged to swing about 45 a fixed normally horizontal axis and which is connected at its upper end to the sleeve 88 in such a manner as to control the horizontal movement of the sleeve. A normally compressed spiral spring 106 tends at all times 50 to rotate the lever 105 in a counter-clockwise direction. The lever 105 is held in its locking position, as shown in the drawing, by a pin 110 which is rigid with the upper portion of the lever and which projects inwardly 55 therefrom. This pin 110 is arranged to engage against a cam 111 which is rigid with a ratchet 112, which is arranged to be actuated by a spring pressed pawl 113 which is mounted upon a plate 114, which is 60 arranged to swing with respect to the ratchet about the axis of the ratchet and to be oscillated by a connecting rod 115, which is pivotally connected at one end to the plate 114 and at its other end to a gear 116 which is 65 arranged to rotate about a fixed axis, and to

be rotated by a worm 117 which is arranged to be actuated by a pinion 118 which normally engages the elongated pinion 87. The arrangement is such that as the turbine 90 rotates the elongated gear 87, the plate 114 70 will be oscillated to rotate the ratchet 112 step by step until the cam 111 is moved out of the way of the pin 110, thus releasing the lever 105 and allowing it to be forced in a counter-clockwise direction by the action of 75 the spring 116 to move the pinion 86 out of engagement with the pinion 85 for rotating the rotor of the gyroscope, and at the same time to move the pin 100 out of engagement with the gimbal ring 81 and thus free the 80 gyroscope.

For adjusting the azimuth ring 65 of the gyroscope to predirec the torpedo 15 upon any desired course, the azimuth ring 65 is surrounded by an annular gear 150, which 85 is insulated therefrom and which is arranged to be engaged by a pinion 151 which is arranged to be actuated by an electrical repeating mechanism 152 which receives its energy through a four-wire cable 153 which 90 leads from the repeating mechanism 152 outwardly through the torpedo and which has a section 154 separably connected to the portion 153 carried by the torpedo by means of a plug 155 which is removably inserted in 95 a socket 166 carried by the torpedo. This removable section 154 is wound upon a reel 170 which is arranged to rotate about an axis fixed with respect to the torpedo tube 10.

The reel 170 is provided with four concentric annular conductors 171 which are insulated from each other and which are connected respectively to the outer ends of the four conductors which form the cable 154. These annular conductors 171 are also 105 arranged to be engaged respectively by four brushes 172 which are connected respectively to the inner ends of four wires which form an outer cable 175 and which are arranged to form continuations of the four wires of 110 the sections of the cable 153 and 154 between the repeating mechanism 152 and the reel 170.

The outer section 175 of the cable includes a return wire 176 which is arranged to be 115 energized by a battery 177. The outer end of the outer section 175 of the cable is connected to an electric motion transmitter 180, which is arranged to be actuated by a pinion 181 which is arranged to be rotated by a 120 gear 182 which is rigid with the lower end of a vertical spindle 183 which is provided at its upper end with a yoke 184 rigid therewith, and which is arranged to rotate about a normally vertical axis fixed with respect 125 to the torpedo tube 10.

For predirec the torpedo in such a manner, that when it is projected from its tube it will assume and proceed upon any predetermined course, a telescope 185 is piv- 130

totally mounted in the yoke 184 to swing about a horizontal axis fixed with respect to the spindle 183, a telescope 185 or other suitable sighting instrument. The arrangement 5 is such that when the telescope 185 is aimed upon a target the motion of the telescope about a vertical axis will be transmitted through the transmitter 180, cable 175, 154, 153, and repeater 152 to the azimuth ring 10 65 to adjust the azimuth ring through the same angle as the telescope is rotated about a vertical axis, but in an opposite direction to predirec the torpedo accordingly.

For the purpose of automatically rendering 15 the telescope 185 inoperative to adjust the azimuth ring 65 after the gyroscope has been unlocked by the movement of the lever 105 in a counter-clockwise direction, the inner end of the return wire 176 is connected 20 to a fixed terminal 190 which is arranged to engage a contact 191 carried by the lower end of the lever 105 but insulated therefrom and connected by a conductor 192 to the electrical repeating mechanism 152, 25 the conductor 192 forming a continuation of the return conductor 176. The arrangement is such that when the lever 105 is in its locking position, as shown in the drawing, the circuit between the inner end of 30 the return wire 176 and the repeating mechanism 152 will be closed, but when the lever 105 has been moved in a counter-clockwise direction from the position shown in the drawing, the circuit through the return wire 35 176 will be broken and consequently the telescope 185 will be rendered inoperative to control the azimuth ring 65.

In the operation of this improved system, 40 with the torpedo in its inoperative position as shown in Fig. 1, when it is desired to predirec the torpedo toward a given target and to discharge the torpedo, the telescope 185 is sighted upon the target and this so adjusts the azimuth ring 65 that when the 45 torpedo has been thrown into the water it will assume and proceed upon a course toward the target as predetermined by the telescope. After the azimuth ring has been thus adjusted the valve 20 is opened to admit air into the inner end of the torpedo tube, whereupon the torpedo is forced outwardly from the tube, and at the beginning of its outward movement the free end of the trigger 93 is moved rearwardly with respect 50 to the torpedo 15 by the fixed lug 94, and this opens communication between the air tank 55 and the turbine 90 which initiates the rotation of the rotor, as hereinbefore described, and when the rotor has been rotated 55 through a predetermined number of revolutions sufficient to permit the rotor to be accelerated up to a predetermined rate of rotation, the pin 100 and the pinion 86 are withdrawn from connection with the gyroscope, thus freeing the gyroscope as herein-

before described. This is accomplished as a result of the releasing of the lever 105, and the releasing of the gyroscope is the result of a counter-clockwise movement of the lever 105, and this separates the lower 70 end of the lever from the fixed contact 190 and thus renders the telescope 185 inoperative to control the azimuth ring 65.

As the torpedo 15 is thus being moved outwardly in the tube 10, the section 154 75 of the cable which connects the torpedo to the reel 170 remains connected to the torpedo at its inner end and is unwound from the reel 170 by the outward movement of the torpedo until all of this section 154 is unwound from the reel 170, whereupon, as this outer section 154 is securely connected at its outer end to the reel 170, the plug 155 ceases to move outwardly and the socket 166 is therefore drawn away from the plug 155, 80 thus disconnecting the torpedo from the outer section 154 of the cable. This outer section 154 of the cable is sufficiently long to permit the plug 155 to remain in its socket 166 until after the torpedo has reached that 85 point in its outward movement with respect to its tube in which the torpedo is entirely outside of the tube 10, and in which rotor 80 of the gyroscope has attained full speed, and the lever 105 has consequently been released 90 and has been permitted to swing in a counter-clockwise direction to simultaneously release the gyroscope, cut off the supply of air from the tank 55 to the turbine 90, and render the telescope 185 inoperative 100 to control the azimuth ring, as hereinbefore described.

To permit the predirec means carried by the torpedo to be controlled by the telescope 185 or sighting means while the torpedo is being projected from the tube and up to the point in the movement of the torpedo when the torpedo is about to be separated from the tube 10, the parts of the predirec means carried by the torpedo are 105 preferably proportional and arranged so that with a suitable predetermined initial pressure of air which is always provided in the tank 55, the rotation of the rotor 80 of the gyroscope will be initiated and ac- 110 celerated during the outward movement of the torpedo while the torpedo is in its tube, and so that the rotor 80 will reach its full speed approximately at that point in the movement of the torpedo where the torpedo 115 is about to be separated entirely from the tube 10.

From the foregoing description, it is evident that by keeping the telescope 185 pointed at the target during the entire time that 120 the torpedo is being discharged from its tube, the torpedo will be predirec in such a manner that after having been projected from its tube it will assume and proceed upon the course predetermined by the tele- 130

scope at the moment that the rotor 80 of the gyroscope has been accelerated up to its full speed and the torpedo is on the point of being separated entirely from its tube.

5 Although only a single form has been shown herein in which this invention may be embodied, it is to be understood that this invention is not limited to any specific construction, but might be applied in various 10 forms without departing from the spirit of the invention or the scope of the appended claims.

Having thus fully described this invention, I claim:

15 1. The combination with a movable body, of automatic steering means carried thereby, including a rotary element, transmission means for adjusting said steering means to predirect said body upon a given course, 20 and means controlled by said rotary element to render said transmission means inoperative to control said steering means.

2. The combination with a movable body, of automatic steering means carried thereby, 25 including a rotary element, and means controlled by said rotary element to render said transmission means inoperative to control said steering means after said rotary element has been rotated from an initial position through a predetermined number of 30 revolutions.

3. The combination with a movable body, of automatic steering means carried thereby, including a rotary element, transmission 35 means for adjusting said steering means to predirect said body upon a given course, and means controlled by said rotary element to render said transmission means inoperative to control said steering means after said rotary element has been rotated from a state 40 of rest to a state of rotation at a predetermined rate.

4. The combination with a movable body, of automatic steering means carried thereby, 45 including a gyroscope, transmission means for adjusting said steering means to predirect said body upon a given course, and means controlled by said gyroscope to render said transmission means inoperative to 50 control said steering means.

5. The combination with a movable body, of automatic steering means carried thereby, including a gyroscope, transmission means 55 for adjusting said steering means to predirect said body upon a given course, and means controlled by said gyroscope to render said transmission means inoperative to control said steering means after said gyroscope has been actuated through a predetermined number of revolutions from a state 60 of rest.

6. The combination with a movable body, of automatic steering means carried thereby, including a rotary element, transmission 65 means for adjusting said steering means to

predirect said body upon a given course, actuating means to initiate and accelerate the rotation of said rotary element, and means controlled by said rotary element to render said transmission means inoperative 70 to control said steering means.

7. The combination with a support, of a movable body carried by said support, automatic steering means carried by said body and including a rotary element, means for 75 projecting said body from said support, means rendered operative by the movement of said body with respect to said support for rotating said rotary element, transmission means extending outside of said body 80 for predirecting said steering means, and means controlled by said rotary element for rendering said transmission means inoperative to control said steering means.

8. The combination with a support, of a 85 movable body carried by said support, automatic steering means carried by said body and including a rotary element, means for projecting said body from said support, means rendered operative by the movement 90 of said body with respect to said support for rotating said rotary element, transmission means extending outside of said body for predirecting said steering means, and means controlled by said rotary element for rendering said transmission means inoperative 95 to control said steering means after said rotary element has been rotated from a state of rest through a predetermined number of revolutions.

9. The combination with a support, of a movable body carried by said support, automatic steering means carried by said body and including a gyroscope, means for projecting said body from said support, means 100 rendered operative by the movement of said body with respect to said support for initiating and accelerating the operation of said gyroscope, transmission means extending outside of said body for predirecting said 105 steering means, and means controlled by said gyroscope for rendering said transmission means inoperative to control said steering means.

10. The combination with a support, of a 115 movable body carried by said support, automatic steering means carried by said body and including a rotary element, pneumatic means for projecting said body from said support, means rendered operative by the 120 movement of said body with respect to said support for rotating said rotary element, transmission means extending outside of said body for predirecting said steering means, and means controlled by said rotary 125 element for rendering said transmission means inoperative to control said steering means.

11. The combination with a support, of a movable body covered by said support, auto- 130

- matic steering means carried by said body and including a rotary element, pneumatic means for projecting said body from said support, actuating means rendered operative by the movement of said body with respect to said support for initiating and accelerating the rotation of said rotary element, transmission means extending outside of said body for predirecting said steering means, and means controlled by said rotary element for rendering said actuating means inoperative to actuate said rotary element, and for rendering said transmission means inoperative to control said steering means.
12. The combination with a support, of a movable body carried by said support, automatic steering means carried by said body and including a rotary element, means for projecting said body from said support, actuating means rendered operative by the movement of said body with respect to said support for rotating said rotary element, transmission means extending outside of said body for predirecting said steering means, means controlled by said rotary element for rendering said actuating means inoperative to actuate said rotary element and to render said transmission means inoperative to control said steering means.
13. The combination with a support, of a movable body carried by said support, automatic steering means carried by said body and including a rotary element, means for projecting said body from said support, actuating means rendered operative by the movement of said body with respect to said support for rotating said rotary element, transmission means extending outside of said body for predirecting said steering means, means controlled by said rotary element for rendering said actuating means inoperative to actuate said rotary element and to simultaneously render said transmission means inoperative to control said steering means.
14. The combination with a support, of a movable body carried by said support, automatic steering means carried by said body and including a rotary element, means for projecting said body from said support, means rendered operative by the movement of said body with respect to said support for rotating said rotary element, transmission means extending outside of said body for predirecting said steering means, and means controlled by said rotary element for rendering said transmission means inoperative to control said steering means, said transmission means being operative to control said steering means while said body is moving with respect to said support for an appreciable period before being rendered inoperative by said rotary element.
15. The combination with a support, of a movable body carried by said support, automatic steering means carried by said body and including a gyroscope, means for projecting said body from said support, means rendered operative by the movement of said body with respect to said support for actuating said gyroscope, transmission means extending outside of said body for predirecting said steering means, and means controlled by said gyroscope for rendering said transmission means inoperative to control said steering means, said transmission means being operative to control said steering means while said body is moving with respect to said support for an appreciable period before being rendered inoperative by said gyroscope.
16. The combination with a support, of a movable body carried by said support, automatic steering means carried by said body and including a gyroscope, means for projecting said body from said support, means rendered operative by the movement of said body with respect to said support for actuating said gyroscope, transmission means extending outside of said body for predirecting said steering means, means controlled by said gyroscope for rendering said transmission means inoperative to control said steering means, said transmission means being operative to control said steering means while said body is moving with respect to said support for an appreciable period before being rendered inoperative by said gyroscope, and said transmission means being arranged to be disconnected by said body as a result of the movement of said body through a predetermined distance from an initial position.
17. The combination with a movable body, of automatic steering means carried by said body and including a rotary element, actuating means for rotating said rotary element, transmission means for predirecting said steering means, and means controlled by said rotary element for rendering said actuating means inoperative to actuate said element and for rendering said transmission means inoperative to predirect said steering means.
18. The combination with a movable body, of automatic steering means carried thereby, and including a rotary element, actuating means for rotating said element, and transmission means for adjusting said steering means to predirect said body upon a given course, said transmission means being arranged to be rendered inoperative as a result of the rotation of said element.
19. The combination with a movable body, of automatic steering means carried thereby, and including a rotary element, actuating means for rotating said element, and transmission means for adjusting said steering means to predirect said body upon a given course, said actuating means and said trans-

mission means being arranged to be rendered inoperative as a result of the rotation of said element.

20. The combination with a movable body, of automatic steering means carried thereby and including a rotary element, and transmission means extending outside of said body for adjusting said steering means to predirect said body upon a given course, said transmission means being arranged to be disconnected from said body as a result of the movement of and immediately following said body from an initial position through a predetermined and appreciable distance.

21. The combination with a movable body, of automatic steering means carried thereby, including a rotary element, movable sighting means, transmission means controlled by said sighting means for adjusting said steering means to predirect said body upon a given course, and means controlled by said rotary element to render said transmission means inoperative to control said steering means.

22. The combination with a movable body, of automatic steering means carried thereby, and transmission means extending outside of said body for adjusting said steering means to predirect said body upon a given course, said transmission means being normally detachably connected to said body and arranged to be automatically disconnected from said body as a result of the movement of said body from an initial position through a predetermined distance.

23. The combination with a movable body, of automatic steering means carried thereby, and transmission means for adjusting said steering means to predirect said body upon a given course, said transmission means having a portion extending outside of said body and arranged to travel in unison with said body through a predetermined distance and then to be automatically disconnected from said body as a result of the movement of said body beyond said distance.

24. The combination with a torpedo, of automatic steering means carried thereby, a support for said torpedo, means for projecting said torpedo from said support, and adjusting means detachably connected to said torpedo and arranged to adjust said steering means to predirect said torpedo upon a given course while said torpedo is being projected from said support.

25. The combination with a torpedo, of automatic steering means carried thereby, a support for said torpedo, means for projecting said torpedo from said support, and adjusting means detachably connected to said torpedo and arranged to adjust said steering means to predirect said torpedo upon a given course while said torpedo is being projected from said support, said adjusting means be-

ing arranged to be automatically disconnected from said torpedo as a result of the movement of said torpedo from an initial position upon said support through a predetermined distance with respect to said support.

26. The combination with a torpedo, of automatic steering means carried thereby, a support for said torpedo, means for projecting said torpedo from said support, and adjusting means including sighting means detachably connected to said torpedo and arranged to adjust said steering means while said torpedo is being projected from said support to predirect said torpedo upon a given course.

27. The combination with a torpedo, of automatic steering means carried thereby, a support for said torpedo, means for projecting said torpedo from said support, and adjusting means including a telescope detachably connected to said torpedo and arranged to adjust said steering means while said torpedo is being projected from said support to predirect said torpedo upon a given course.

28. The combination with a torpedo, of automatic steering means carried thereby, a support for said torpedo, and adjusting means for adjusting said steering means to predirect said torpedo upon a given course, said adjusting means including sighting means supported independently of said torpedo, and transmission means detachably connecting said sighting means to said torpedo, said transmission means including an electric cable having a portion extending outside of and detachably connected to said torpedo and movable in unison therewith through a predetermined distance and arranged to be disconnected from said torpedo as a result of the movement of said torpedo beyond said distance.

29. The combination with a torpedo, of automatic steering means carried thereby, a support for said torpedo, and adjusting means for adjusting said steering means to predirect said torpedo upon a given course, said adjusting means including a telescope supported independently of said torpedo, and transmission means detachably connecting said telescope to said torpedo, said transmission means including an electric cable having a portion extending outside of and detachably connected to said torpedo and movable in unison therewith through a predetermined distance and arranged to be disconnected from said torpedo as a result of the movement of said torpedo beyond said distance.

30. The combination with a torpedo, of automatic steering means carried thereby, a support for said torpedo, means for projecting said torpedo from said support, adjusting means including an element supported

- independently of said torpedo, said transmission means between said element and said torpedo, said transmission means being detachably connected to said torpedo and being arranged to permit said element to control said steering means while said torpedo is being projected from an initial position upon said support into another position on said support. 5
- 10 31. The combination with a torpedo, of automatic steering means carried thereby, a support for said torpedo, means for projecting said torpedo from said support, adjusting means including an element supported independently of said torpedo, and transmission means between said element and said torpedo; said transmission means being detachably connected to said torpedo and being arranged to permit said element to control said steering means while said torpedo is being projected from an initial position upon said support into another position on said support, and said transmission means being arranged to be automatically disconnected from said torpedo as a result of the movement of said torpedo beyond said support. 15
- 20 32. The combination with a torpedo, of automatic steering means carried thereby, a support for said torpedo, means for projecting said torpedo from said support, adjusting means including an element supported independently of said torpedo, and transmission means between said element and said torpedo, said transmission means being detachably connected to said torpedo and being arranged to permit said element to control said steering means while said torpedo is being projected from an initial position upon said support into a position where said torpedo is on the point of leaving said support, and said transmission means being arranged to be automatically disconnected from said torpedo as a result of and immediately after the movement of said torpedo from its initial position into a position where the torpedo is entirely outside of said support. 25
- 30

mission means between said element and said torpedo, said transmission means being 35 detachably connected to said torpedo and being arranged to permit said element to control said steering means while said torpedo is being projected from an initial position upon said support into a position where 40 it is about to leave said support.

33. The combination with a torpedo, of automatic steering means carried thereby, a support for said torpedo, means for projecting said torpedo from said support, adjusting means including an element supported independently of said torpedo, and transmission means between said element and said torpedo, said transmission means being detachably connected to said torpedo and being 45 arranged to permit said element to control said steering means while said torpedo is being projected from an initial position upon said support into a position where said torpedo is on the point of leaving said support, and said transmission means being arranged to be automatically disconnected from said torpedo as a result of and immediately after the movement of said torpedo from its initial position into a position where the torpedo is 50 entirely outside of said support. 55

Signed at New York in the county of New York and State of New York this 19th day of June A. D. 1917.

ALBERT D. TRENOR.
